UNITED STATES PATENT OFFICE.

JACOB MAZER, OF PITTSBURGH, PENNSYLVANIA, ASSIGNOR TO MAZER ACOUSTILE COMPANY, OF PHILADELPHIA, PENNSYLVANIA, A CORPORATION OF PENNSYLVANIA.

ACOUSTIC ELEMENT.

1,318,574.

Specification of Letters Patent.

Patented Oct. 14, 1919.

Application filed October 2, 1916. Serial No. 123,430.

To all whom it may concern:

Be it known that I, JACOB MAZER, a citizen of the United States, and resident of Pittsburgh, in the county of Allegheny and 5 State of Pennsylvania, have invented a new and useful Improvement in Acoustic Elements, (Case 2;) and I do hereby declare the following to be a full, clear, and exact description thereof.

10 My invention relates to an acoustic element and is particularly concerned with the provision of the improved element which may be employed in improving the acoustic properties of churches, auditoriums or other 15 apartments.

The object of my invention is to provide an acoustic element or unit that may be installed without the employment of skilled labor, and of sufficient tensile strength to 20 withstand the ordinary handling to which such material is subjected in transit or in being attached to the wall surface.

In the accompanying drawing Figure 1 is a perspective view showing the divided 25 sections, and Fig. 2 is a cross-sectional view.

In the drawing the numeral 8 indicates a felt layer with a backing 9 of corrugated material which may be formed of asbestos board, fiber board or any other material 30 having sufficient body and coherence to retain its shape so that the acoustic unit combined therewith may not be distorted or twisted out of shape. The fibrous material or felt 8 may be secured to this corrugated

backing in any suitable manner either by 35 an adhesive substance or by wire staples 10 or the like. The units are of a convenient size for handling. The numeral 11 indicates the lines of separation between the different sheets of units. The combined backing 40 and fibrous acoustic material may be handled without danger or changing the shape of the unit or altering its acoustic value. Moreover the backing affords a substantial means for fastening the unit to the 45 wall. It further affords the necessary tensile strength which is lacking in the fibrous material, and so enables the units to be handled without being impaired or distorted, or its acoustic value impaired. 50

What I claim is:

A self contained acoustic element comprising a foundation member constructed to form air spaces at one side of the element, and to afford sufficient tensile strength 55 thereto for the necessary handling of the element and maintain the same unimpaired by said handling, and a layer or covering of fibrous material secured to said foundation material and which layer is of such 60 loosely associated fiber as of itself to lack sufficient tensile strength for handling.

In testimony whereof I, the said JACOB MAZER, have hereunto set my hand.

JACOB MAZER.

Witnesses:

JOHN F. WILL,
J. R. KELLER.
